and Walter A. Lindsay, Los Angeles, Calif.

Application February 25, 1930, Serial No. 431,090

8 Claims. (Cl. 68—15)

This invention relates to washing machines of the type employed for agitating articles in a liquid and separating the liquid from said articles.

5 An important object of the invention is to elevate the articles above the liquid body in which agitation takes place and subject said articles while raised to centrifugal action in order to separate from said articles any of the liquid that is on or in them when raised out of the bath.

10 Another object is simplicity of construction and operation.

Another object is reliability in use.

15 Another important object is to effect raising of the articles out of the bath by mechanical power that is employed in agitating them while in the bath.

Other objects and advantages will appear in the subjoined detailed description.

20 The accompanying drawings illustrate the invention. Fig. 1 is a side elevation of a washing machine constructed in accordance with the provisions of this invention.

25 Fig. 2 is a plan view of Fig. 1, cut short lower. Fig. 3 is an enlarged sectional view on the line indicated by 3—3, Fig. 2, the basket being shown in lowered position in solid lines and in raised position in broken lines.

30 Fig. 4 is an enlarged horizontal section on the line indicated by 4—4, Fig. 3, assuming that the spindle is raised to its upper position.

Fig. 5 is an enlarged fragmental plan view, partly in section, from the line indicated by 5—5, Fig. 3, assuming that the spindle is in its lower position.

35 Fig. 6 is an enlarged broken plan view, partly in section, from the line indicated by 6—6, Fig. 3.

Fig. 7 is a fragmental view, partly in section, from the line indicated by 7—7, Fig. 6.

40 There is provided a tank 8 adapted to hold the liquid bath A, and there is rotatably mounted within the tank 8 a basket 9 adapted to contain the articles that are to be immersed in the bath, the basket being perforate or provided with openings 10 through which the liquid can readily enter and leave the basket 9.

45 Within the basket 9 is an agitator 11 which may comprise any desired number of vertically arranged blades 12 projecting radially from a central vertical sleeve 13 that constitutes the stem of the agitator. The stem 13 surrounds a vertical spindle 14 which is rotatably mounted in a bearing 15 that extends from the bottom of the tank approximately halfway to the top of said tank. The lower end of the bearing 15 is provided with a flange 16

which is secured by fastening devices 17 to the bottom 18 of the tank.

The spindle 14 projects through the tank bottom 18 and is adapted to be releasably connected to a spur gear 19 by a clutch of which one member 20 is fixed to the spindle 14 and the other member 21 is fixed to the gear 19. Raising and lowering of the spindle 14, and with it the clutch member 20, is accomplished by a shifting fork 22 which projects between the clutch member 20 and a spur gear 23 which is also fixed to the spindle 14 at a slight distance above the clutch member 20. The shifting fork 22 extends beneath the tank bottom 18 to one side thereof and is operated by a rod 24 which is pivoted at 25 to the shifting fork 22 and works in guides 26 secured to the circumferential wall of the tank. The upper end of the rod 24 is provided with a handle 27 and a shoulder 28 on said rod is adapted to engage one of the guides 26 to limit downward motion of the rod 24 and accordingly restrict upward movement of the spindle 14. The shifting fork 22 has its fulcrum 29 supported in the wall of the tank 8 beneath the bottom 18.

The gear 19 turns on a supporting frame 30 which is attached to the bottom portion of the tank a stub shaft 31 being screwed into or otherwise secured to said frame to form the axis for the gear 19.

The gear 19 is turned through an idler gear 32 by another spur gear 33 that turns on a stub shaft 34 screwed into or otherwise secured to the frame 30. Also the idler gear 32 turns on a stub shaft 35 which is screwed into or otherwise secured to the frame 30.

35 The gear 33 is connected by a hub 36 to a worm gear 37 in mesh with a worm 38 on a worm shaft 39 driven by a pulley 40 on which runs a belt 41 that, in turn, is driven by a pulley 42 on the shaft of a motor 43 which is suitably mounted on the frame 30. It is to be understood that the clutch member 21 may be driven through the agency of any other suitable driving mechanism than that just described, so as to produce rotary motion of the spindle 14.

45 The spindle may also be oscillated by the provision of a suitable means which, in this instance, is constructed as follows. In this instance this means is driven off of the worm gear 37 and comprises a rack bar 44 that is pivoted at 45 to the worm gear 37. The rack bar 44 works through a guide 46 so that the path of movement of its teeth, when the worm gear 37 rotates, intersects the path of movement of the gear 23 when the shifting fork 22 is moved into a position to raise

the spindle sufficiently to bring the gear 23 opposite to the rack bar.

It is now clear that the spindle 14 may be either rotated or oscillated, according to the position of the clutch member 20.

5 A means is provided to transmit motion of the spindle 14 to the agitator 11 and, in this instance, this is effected as follows: Secured to the spindle 14 is a clutch member 47 which, when the spindle 10 is raised into its upper position, engages with an internal clutch member 48 formed in the upper end of the stem 13 so that when the clutch members 47, 48 are engaged, oscillation of the spindle 14 will produce oscillation of the agitator.

15 A suitable means is provided for effecting raising of the basket 9 and, in this instance, this means is constructed as follows: Rotatably mounted on the bearing 15 is a hollow screw 49 of which the thread is external. This screw 49 is turned 20 when the clutch member 47 is in engagement with another clutch member 50 formed in the upper end of said screw 49. The clutch members 48 and 50, in this instance, are in the form of internal 25 spur gears while the clutch member 47 is also in the form of a gear adapted to engage either of the clutch members 48, 50, according to the position of the spindle 14.

30 Beneath the basket 9 is a nut on which the basket rests, said nut, in this instance, comprising segmental sections 51 which are pivoted at one end at 52 to a bearing member 53 that constitutes a portion of the basket bottom, said bearing member 53 being tubular and surrounding the screw 49 but being out of engagement with said 35 screw. When the nut sections 51 are closed together the threads of said sections engage the thread of the screw 49 so that when the screw 49 is rotated the nut will ride up the screw to near the upper end thereof. The nut in its ascent 40 carries the basket with it and when the basket reaches its upper position, a shoulder 54 in the groove of the screw thread of one of the nut sections 51 is engaged by a shoulder 55 on the screw 49 which, since it is rotating, then causes the basket 9 to rotate. When the basket contains, 45 for example, articles that are to be laundered, the rotary motion of the basket is transmitted to said articles and from said articles to the agitator, thus rotating the agitator with the basket.

50 The nut sections may be operated into open and closed positions by any suitable means and, in the present instance, the construction relied upon includes a pair of links 56 pivoted at 57 to the respective nut sections 51 and pivotally connected 55 at 58. Pivoted at 59, substantially midway of the links 56, are other links 60 which are pivotally connected at 61, the pivot 61 also connecting the links 60 to the fork 62 of the operating rod 63 which extends horizontally beneath the bottom 60 of the basket to one side thereof.

65 The outer end of the rod 63 is pivoted at 64 to a crank arm 65 that is fixed to a rock shaft 66 that turns in bearings 67 secured to the peripheral wall of the basket. The shaft 66 extends to the top of the basket and is there provided with a handle 68 whereby the rock shaft may be readily turned. The rock shaft is prevented from downward movement by a collar 69 thereon engaging the upper face of one of the bearings 67.

70 It is desirable that, when the basket is revolving, any liquid, that may be sprayed on the articles within the basket, in discharging through the openings 10, will not contaminate the liquid bath within the tank 8 and, accordingly, we have 75 provided an annular trough 70 that extends

around the inner face of the tank and that is suitably attached thereto. The trough 70, in this instance, is positioned midway of the height of the tank or approximately at the level of the bottom of the basket when the basket is in its raised position. The trough 70 is provided with an outlet 71 that opens through the side of the tank and that, in this instance, communicates with a pipe 72 provided with a valve 73.

5 10 If desired, the tank may be mounted on a suitable carriage, such as that indicated by the character 74, said carriage, in this instance, being provided with castors 75 so as to enable the tank to be readily moved from one location to another.

15 Assuming, for example, that the articles to be operated on by the centrifuge are articles that are to be laundered, the invention operates as follows: The tank 8 will be supplied with wash water and soap and the articles to be laundered 20 will be placed in the basket 9. The handle 68 will be operated to a position that will spread the nut sections 51. The clutch member 20 will be operated into a position to free it from the clutch member 21 thus, at the same time, causing the 25 gear 23 to engage the rack bar 44 and the clutch members 47, 48 to engage. The motor will now be switched on, thereby causing oscillation of the agitator 11 so as to wash the articles in a manner well understood in the art relating to 30 washing machines that are provided with this type of agitator. After the agitator has been operated a sufficient length of time to effect cleansing of the articles, the operator will operate the handle 27 into a position to engage the 35 clutch members 20, 21, disengage the gear 23 from the rack bar 44, disengage the clutch members 47, 48 and engage the clutch members 47, 50, thereby effecting a rotation of the screw 49. The operator will then move the handle 68 into a 40 position that will close the nut sections 51 into engagement with the thread of the screw 49, resulting in the nut, and with it the basket, being raised from the position shown in solid lines in Fig. 3 to the position indicated in broken lines. 45

As the basket rises, the wash water drains from the articles and from the basket through the openings 10 and when the basket reaches its upper position the shoulders 54, 55 will engage, thus causing the stem to revolve and with it the 50 basket and the articles therein. The centrifugal force set up by this rotation forces the wash water out of the articles being laundered and this water passes through the openings in the peripheral wall of the basket and is thrown 55 against the inner face of the upper portion of the tank whence it drains downwardly into the trough 70 which overflows into the tank, the valve 73 being closed. When wash water is no longer being expelled from the articles, the valve 60 73 will be opened so as to discharge any water that thereafter enters the pipe 72 therefrom, and the articles may then be rinsed by spraying them with clear water while the basket is rotating. The rinse water will be thrown out into 65 the trough 70 and will pass into the pipe 72, and thence to a waste line, not shown.

70 The articles, after thus being rinsed, may then be removed from the basket and the basket lowered and a fresh supply of articles be placed 75 therein for washing and rinsing by repeating the cycle of operations above described.

To lower the basket, the handle 68 will be moved into a position to spread the nut sections 51 so as to disengage them from the thread of 75

the screw 49, whereupon the basket will be caused to descend by its own weight until the nut 51, 51 comes to rest on the flange 16.

We claim:

5. 1. A washing machine including a tank, a screw rotatably mounted in the tank, a basket in the tank, nut sections movably connected with the basket and engageable with the thread of the screw when said sections are closed together, an agitator movably mounted in the basket, clutch members on the screw and agitator, a third clutch member shiftable alternately into engagement with the first mentioned clutch members, and a means operable to either oscillate 10 or rotate the third clutch member according as to whether the third clutch member is engaged with the clutch member on the agitator or with the clutch member on the screw, respectively.
2. A washing machine including a tank, a hollow screw rotatably mounted in the tank, a basket in the tank, nut sections movably connected with the basket and engageable with the thread of the screw when said sections are close together, an agitator movably mounted in the basket, clutch 15 members on the screw and on the agitator, a spindle mounted to move endwise within the screw, a clutch member on the spindle adapted when the spindle is moved to one position to engage the clutch member on the agitator and when the spindle is moved into another position to engage the clutch member on the screw, co-operating means on the screw and nut adapted to engage when the basket is raised by the nut to cause rotation of said basket, and means operable 20 selectively to oscillate and rotate the spindle.
3. A washing machine including a tank, a hollow screw rotatably mounted in the tank, a basket in the tank, nut sections movably connected with the basket and engageable with the thread of the screw when said sections are close together, an agitator movably mounted in the basket, clutch members on the screw and on the agitator, a spindle mounted to move endwise 25 within the screw, a clutch member on the spindle adapted when the spindle is moved into one position to engage the clutch member on the agitator and when the spindle is moved into another position to engage the clutch member on the screw, means on the screw adapted to engage with the nut when the nut is raised by the screw to cause rotation of said nut and basket, a fourth clutch member mounted on the spindle, a fifth rotatably mounted clutch member engageable by the fourth clutch member when the spindle is in the second mentioned position, a means to rotate the fifth clutch member, and a means to oscillate the spindle when the fourth and fifth clutch members are disengaged.
4. A washing machine including a tank, a basket rotatably mounted in the tank, an agitator rotatably mounted in the basket, a motor, a means operable by the motor to raise the basket, a means operable by the motor to oscillate the agitator while the basket is in its lower position,
- and a means automatically operable by the basket raising means when the basket reaches its upper position to rotate the basket.
5. A washing machine including a tank, a basket rotatably mounted in the tank, an agitator rotatably mounted in the basket, a motor, mechanism driven by the motor operable to raise the basket and to thereafter automatically rotate it while maintaining it in raised position and to oscillate the agitator while the basket is in its lower position, and means to control said mechanism to obtain the different operations at will.
6. A washing machine comprising a tank, a basket rotatably mounted in said tank, a shaft movable between an upper and a lower position, means for rotating said shaft, a hollow screw rotatably mounted vertically in said tank concentrically about said shaft, clutch means for rotatably connecting said shaft to said screw in response to downward movement of said shaft, means attached to said basket having threads registerable with said screw whereby said basket and threaded means attached thereto are elevated with respect to said screw by relative rotation therebetween, and means for forcing rotation of said basket with said screw after a predetermined relative movement therebetween.
7. A washing machine including a tank, a perforated basket rotatably mounted in the tank, a threaded member attached to said basket, a rotatably mounted screw having threads engageable with said first threaded member whereby rotation of said screw with respect to said basket moves said first threaded member and said basket upwardly along the screw cooperating stops on said screw and on said threaded member respectively for limiting upward movement of said basket in response to the rotary motion of said screw with respect to said basket and causing them to rotate together thereafter, said stops having cooperating impact faces substantially in radial planes with respect to the axis of said screw whereby rotation of said screw with respect to said threaded member is limited without wedging the screw and the threaded member together.
8. A washing machine comprising a tank, a basket rotatably mounted in the tank and movable between lower and upper positions therein, an agitator rotatably mounted in said tank within said basket, a basket-raising means comprising a vertical screw concentrically positioned within said basket and a cooperating nut means secured to said basket, means for preventing relative rotation between said screw and nut when said nut means reaches a predetermined height on said screw, driving means comprising a rotating member and an oscillating member, and means for selectively coupling either said screw to said rotat- ing member or said agitator to said oscillating member.
